TRANSPORTATION CHAIR

Benjamin H. Drake, Stockton, Calif.

Application April 9, 1937, Serial No. 135,966

3 Claims. (Cl. 155—116)

This invention relates generally to a selectively reclining chair and in particular is directed to the structure of a chair designed for transportation use such as in modern trains, busses or aircraft.

The principal object of my present invention is to provide a transportation chair which when moved to a reclining position will afford comfort to the occupant and yet will not cause annoyance or crowding of the occupant of the chair behind as now often occurs with other chairs whose back portions deflect rearward materially when the chair is reclined.

Another object of my invention is to provide a transportation chair which, when moved from an upright to a semi-reclining position, will provide greater comfort due to the even distribution of the occupant's weight from the shoulders to the knees with no tendency for the occupant to slide out of the chair.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation illustrating my improved chair in upright position; the fully reclined position being shown in dotted lines.

Figure 2 is an enlarged sectional elevation of the chair in upright position with only the near side frame member and track removed; the semi-reclining position being shown in dotted lines.

Figure 3 is an enlarged fragmentary section taken on line 3—3 of Fig. 2.

Figure 4 is a fragmentary front end view of one of the forward seat supporting rollers.

Figure 5 is an elevation illustrating the particular control lever for use on the aisle side of the chair.

Figure 6 is an elevation of the control lever as constructed for use on the side of the chair adjacent a wall.

Referring now more particularly to the characters of reference on the drawings, my improved chair comprises a substantially rectangular main frame 1 supported adjacent each corner by rigid legs 2. A separate seat frame 3, having a seat cushion 4 thereon, is supported at its forward end upon transversely spaced rollers 5 mounted on the front cross member of the main frame 1.

Each of these rollers rides on a rail 6 on the bottom of seat frame 3, a bent over finger 7, formed with the roller bracket, extending over the top of the rail in order to prevent separation of the roller and rail and to thus maintain the seat frame in place.

Rollers 8 are fixed on and extend downward from the seat frame 3 adjacent the back corners thereof; said rollers riding in tracks 9 secured to the inner faces of the sides of the main frame 10. These tracks are formed with a curved dip intermediate their ends for the purpose hereafter described. A horizontal transverse shaft 10 is journaled between the sides of the main frame 1 below the seat frame, the shaft having fixed radial arms 11 projecting upward therefrom alongside the seat frame on both sides and at a slight normal rearward slope. Substantially horizontal links 12 are pivoted at their rear ends to the upper ends of arms 11, and at their forward ends 20 to the sides of the seat frame as at 13.

Connecting arms 14 are fixedly secured to the sides of the seat frame adjacent the rear ends thereof and extend rearward to pivotal connection as at 15 with the sides of the seat back 16 at 25 its lower end. Parallel and rearwardly sloping channels or tracks 17 are mounted on the main frame and project upward along the sides of the seat back 16. Rollers 18 are secured to the sides of the seat back intermediate the ends thereof and ride in the tracks 17. Arm rests 19 are pivoted on the sides of and project forward from the seat back, the forward ends of the arm rests being supported by links 20 pivoted at the upper end to the arm rests and at the lower end to the 30 seat frame. A shield 21 extends from the transverse rock shaft 10 to the bottom edge of the seat back. The shield is hinged on the shaft and its upper end is guided in channels 21a attached to the back 16 at the sides. This does not interfere with the action of the chair and seals the only space where feet might get pinched, while providing all possible foot room under the chair from behind.

A radial control lever 22 is fixed on one end of shaft 10 outwardly of the main frame and projects upward to a point alongside one arm rest. A catch releasing grip is mounted on the upper end of the lever and includes a metallic loop 23 offset outwardly of the chair, and a pad 24 secured thereon. A catch release member 25 for engagement with the fingers is disposed within the loop and with its depending catch or pawl P slidably mounted in a sleeve 26 which is preferably formed integral with lever 22 and loop 23. 55

- The lower end of said depending catch is notched to engage in corresponding stepped notches 27 in the upper edge of a quadrant 28 secured to the main frame. A spring S normally holds the 5 catch in a quadrant engaging position. The notches of the quadrant and the notched end of the catch are stepped in order to effect a positive engagement and yet cause the catch when fully seated to fit snugly in notches 27.
- 10 The releasing grip shown in Fig. 5 is designed for use on the aisle side of the chair while the grip shown in Fig. 6 has an oppositely offset grip loop 23a and cooperating parts, this being designed for use on the side of the chair adjacent 15 a wall where the space between said wall and the chair is very limited.

Transversely spaced arms 29 are hinged at their forward ends to the main frame as at 30 and extend rearwardly beneath the seat frame, their 20 inner ends being supported on compression springs 31 seated on a cross bar 32. Rollers 33 are mounted on the seat frame and ride on the upper face of the spring supported arms and which arms thus act or tend to return the seat frame to 25 a horizontal position, thus making for easier operation.

In use, the chair may be shifted from an upright position to a semi-reclining or reclining position by the occupant who need only place his hand on 30 the releasing grip, pull the catch release member up and then push the lever 11 forward. This shifts the seat forward and reclines the back while at the same time lowering the seat at the rear whereby the occupant will not tend to slide 35 forward on the seat as the chair reaches a semi-reclining position as shown in dotted lines in Fig. 2. Such lowering of the rear portion of the seat is accomplished by the use of the track 9 curved intermediate its ends. Due to the particular con- 40figuration of the track, the seat—after lowering at the rear as the chair reaches a semi-reclining position—will rise again to a substantially horizontal position as the chair is fully reclined, as shown in dotted lines in Fig. 1. To return the 45 chair to an upright position the procedure is merely reversed and the lever pulled backward, springs 31 doing most of the lifting work.

By constructing the chair as heretofore de- 50scribed, a movement of the seat and seat back from a normal or upright position to a reclining position can be accomplished with a relatively small amount of rearward deflection of the seat back. This is extremely advantageous in that when one chair is in reclining position, the occ- 55upant of the next rearward chair is not crowded or otherwise annoyed. Also, but little physical effort is needed in both lowering or raising the chair.

From the foregoing description it will be readily seen that I have produced such a device as substantially fulfills the objects of the invention as set forth herein.

While this specification set forth in detail the 5 present and preferred construction of the device, still in practice such deviations from such detail may be resorted to as do not form a departure from the spirit of the invention, as defined by the appended claims.

Having thus described my invention, what I 10 claim as new and useful and desire to secure by Letters Patent is:

1. In a reclining chair, a main frame, a seat frame and means mounting the seat frame on the 15 main frame for forward movement from a retracted position; said means including supporting tracks mounted on the main frame extending along the sides thereof from adjacent its rear end, said tracks being substantially horizontal 20 at each end and being formed with a curved dip intermediate their ends, rollers on the seat frame adjacent its rear end and engaging the tracks, and rollers on the main frame adjacent its front end slidably supporting the seat frame.

2. In a reclining chair, a main frame, a seat frame and means mounting the seat frame on the main frame for forward movement from a retracted position; said means including a longitudinal track member mounted on the seat frame 30 whose end portions are substantially aligned and which is formed with a curved dip between said portions, an element on the seat frame adjacent its rear end engaging said track member, and means between the frames slidably supporting the 35 seat frame at a fixed level at the front end of the main frame.

3. In a reclining chair, a main frame, a seat frame and means mounting the seat frame on the main frame for forward movement from a retracted position; said means including means between the frames slidably supporting the seat frame at a fixed level at the front end of the main frame, a longitudinal track member mounted on one frame, and extending forwardly from the rear end thereof, and an element on the other frame engaging said track member; the end portions of said member being substantially aligned and said member being formed with a curvature in a vertical plane between said aligned portions, the element engaging the member at such a point in its length when the seat frame is fully retracted, and the curvature of said member extending in such direction that the rear end of the seat frame will lower after a predetermined amount of advancing movement from a retracted position, and will then rise when fully advanced.

BENJAMIN H. DRAKE.
